UNITED STATES PATENT OFFICE

2,677,474

SILO UNLOADER

Robert J. Long, Evanston, and Robert A.
Van Nest, La Grange Park, Ill.

Application June 26, 1952, Serial No. 295,772

4 Claims. (Cl. 214—17)

1

The present invention relates to silo unloaders, and is particularly concerned with an improved mechanical silo unloader of the type adapted to be supported by means of a winch and cables extending downwardly from the top of the silo to the level of ensilage therein.

One of the objects of the invention is the provision of an improved mechanical type of silo unloader, by means of which blowers and blower conveyors may be eliminated and by means of which constant unloading and conveying of the ensilage to the discharge chute is assured.

Another object of the invention is the provision of an improved silo unloader assembly which is adapted to be maintained in centered position in the silo, and which is dependable, capable of economical manufacture, and adapted to be used for a long period of time without necessity for repair or replacement of any of its parts.

Another object of the invention is the provision of an improved silo unloader which will operate equally well in the winter time when the ensilage may be frozen, and which will unload the hardest frozen ensilage, corn or grass.

Another object of the invention is the provision of an improved form of drive mechanism for driving the rotating screw conveyors which also travel about in a circle covering the full area of a silo, while still maintaining an upper part of the apparatus in fixed position, communicating with a radially extending conveyor for conveying ensilage from the central part of the mechanism to the gate.

Another object of the invention is the provision of an improved boom construction by means of which the whole mechanism may be carried by three cables from a tripod at the top of the silo.

Other objects and advantages will be apparent from the following description and the accompanying drawings, in which similar characters of reference indicate similar parts throughout the several views.

Referring to the drawings, of which there are eight sheets, accompanying this specification,

Fig. 1 is a vertical sectional view taken on a plane passing diametrically through a silo and its discharge chute, showing our silo unloader in operating position at the top of the silo;

Fig. 2 is a top plan view, omitting the driving dog and screw conveyors;

Fig. 3 is a sectional view taken on the plane of the line 3—3 of Fig. 1, looking in the direction 55

2

of the arrows, showing the screw conveyors and driving dog;

Fig. 4 is a fragmentary side elevational view showing the driving mechanism;

Fig. 5 is a fragmentary sectional view taken through the gear housing of Fig. 4, showing a preferred form of driving mechanism;

Fig. 6 is a fragmentary, vertical sectional view taken on the plane of the line 6—6 of Fig. 5;

Fig. 7 is a fragmentary, elevational view taken on the plane of the line 7—7 of Fig. 5;

Fig. 8 is a side elevational view of a preferred form of supporting boom construction;

Fig. 9 is a top plan view of the boom construction of Fig. 8;

Fig. 10 is a fragmentary side elevational view of the end construction of each of the booms of Fig. 8; and

Fig. 11 is a fragmentary top plan view of Fig. 10.

Referring to Fig. 1, 10 indicates in its entirety the silo which has a cylindrical wall 11, a radially projecting chute 12, located opposite the removable boards 13, slidably mounted in a vertical opening 14, in one side of the silo.

15 The supply of ensilage is indicated at 15 and the silo unloader is indicated in its entirety by the numeral 16. The silo unloader 16 preferably includes an upper cylindrical housing 17, which has attached to its suitable brackets 18, for supporting a belt conveyor unit 19, Fig. 1, Fig. 4.

20 The conveyor unit 19 preferably includes a pair of side boards 20, secured to longitudinally extending frame members 21 which carry bearings 22, at each end for rotatably supporting the drums 23, 24, which carry the belt 25.

25 The belt may comprise leather, rubber or other fabric, and preferably is provided with wooden slats 26 located at regular spaced intervals, such as 8 inches apart, for carrying the ensilage to the chute 12 between the side boards 20.

The drums 23, 24 comprise substantially cylindrical metal or wooden drums provided with a slight crown for centering the belt 25. The brackets 18 carrying bearings which rotatably support an extension of the shaft 27 for drum 23, and drum 24 is supported adjacent the cylindrical housing 17 as closely as possible to the screw 28, which is carried by a shaft vertically and centrally of the housing 17 for lifting the ensilage and discharging it upon the belt 25.

30 Housing 11 has a hole adjacent to but spaced from the belt 25 and drum 24, and extending above the belt 25 for discharge of ensilage from the housing 17. A cable 29 extends upward from

the frame of the conveyor 19 at its free end for supporting the conveyor at the desired level, the conveyor pivoting on the shaft 27 when required to do so.

The housing 17 supports an annular member 30, Fig. 4, having three cylindrical metal socket members 31 attached thereto, each socket carrying a radially extending tubular frame member 32, 33, 34.

The tubular members 32-34 are employed to center the mechanism in the silo and each of the tubular members 32-34 is provided with a telescoping smaller tubular extension 35, which extends into the tubular members 32, 33 or 34, and is engaged by a compression spring 36, which in turn may be seated upon a seat 37, mounted upon a cross bolt 38.

A plurality of holes are provided for the cross bolt 38 so that the extensions 35 may be sprung pressed outward when used in silos of different sizes.

Adjacent its end each extension 35 is provided with a through eye bolt, the eye being used for attachment to one of the cables 40, of which there are three, for supporting the radial tubular members 32-34. Each extension supports a U-shaped bearing bracket 41, having a transverse stub shaft 42 for rotatably supporting a vertical roller 43.

Thus all of the extensions 35 have their rollers 43 urged into engagement with the inside of the wall of the silo in such manner that the rollers may roll up or down as controlled by the cables 40.

The springs 36 being arranged to provide extensions 35 of equal length, and all exerting the same pressure, the mechanism will be centered in the silo and maintained in centered position by means of the springs 36 and tubular members 32-35.

The housing 17 supports a drive motor 44 at its upper end, and the drive motor has a shaft 45 extending downward through the housing for driving the screw 28 and radially extending choppers 46 carried by the screw shaft 45 at the lower end of the housing.

The motor 44 is connected by suitable gearing contained in reduction gear box 47 to the drive shaft 27 of the conveyor 19, in such manner as to drive the upper side of the belt 25 radially outward.

At its lower end the housing 17 supports a rotatable housing extension 48 which is open at its bottom, where the shaft 45 carries the rotary choppers 46 which move the ensilage away from beneath the housing 48.

The lower housing 48 is adapted to rotate on the upper housing 17, and carries a gear box 49 at one side with suitable gears, such as a worm gear, engaging a screw upon a shaft 50.

The worm gear 51 is mounted upon a radial tubular shaft that extends outward to a point adjacent the silo wall, where the shaft has mounted upon it a substantially cylindrical, heavy cast metal driving dog or wheel 53. This driving dog or wheel 53 is rotated by the tubular shaft 52, and the drive wheel 53 has any suitable form of driving ribs 54 on its tread for engaging the ensilage and causing it to move slowly by rolling motion over the ensilage to rotate the housing 48.

A fixed shaft 55 extends through the tubular shaft 52 and is provided on its end with an upwardly extending bracket 56, carrying a vertical stub shaft 57, upon which a guide roller 58 is rotatably mounted. Guide roller 58 and shaft 55 provide a fixed frame extending from housing 48

to the silo wall and further assure the centering of the housing 48 relative to the silo.

The housing 48 has an opening at one side exposing the screw 28, and it is provided with a box-like extension 59, Fig. 3, at each side, provided with bearings for the two screw shafts 60, 61.

Box 59 supports a pair of longitudinally extending frame members 62, which in turn support telescoping frame members 63, joined together at their outer ends to form a frame 64 with bearings for the other ends of shafts 60, 61.

The frame 64 is open on its lower side but may be closed at 65 on its upper side and at its outer end it has a bracket for supporting one or more rollers 66, like the roller 58, for rolling around the inside of the silo wall.

The shafts 60, 61 may carry screws 67, the rise of which may be greater at outer sections 68 on the shafts 60, 61. The screw flanges preferably carry outwardly extending knives bolted to the screw flanges at regularly spaced intervals, there being a greater number of knives 69 on the outer screw sections 68, near the silo wall where more frozen ensilage is to be encountered.

Each shaft 60, 61 extends into the gear box 49, where it is provided with a beveled gear driven by suitable gearing from the shaft 50 which drives the shaft 52. The screws 67 and 68 rotate and chop the ensilage loose from the mass and cause it to progress longitudinally of the frame members 62, 63, the direction of the screw being such as to also lift the ensilage from the mass as it progresses radially inward until it is fed into the housing 48, where it is engaged and lifted by the screw 28 to the conveyor 19.

The housing 17 is fixed, and at its lower end it supports a ring bearing member for the rotating housing 48. Ring bearing member 70 has a laterally projecting arm 71, with a bearing for the shaft 50, which is provided with a V-pulley 72 on its upper end.

A two ring pulley 73 is rotatably mounted on housing 17, and one of the V-grooves 74 drives the belt 75, which extends to pulley 72. The other V-groove 76 is driven by the belt 77 from a V-pulley 78 carried by shaft 79.

Shaft 79 may have a pair of bearings 80, carried by housing 17, and at its upper end it carries a V-pulley 81, with a belt 82, driven by the V-pulley 83 on the motor shaft 45. By means of the ring, V-pulleys 73, which are integrally joined together and which rotate on the shaft housing 17, the screw shafts 60 and 61 may be driven through suitable gears, and the driving dog wheel 54 may be driven to cause the lower housing 48 to rotate with the dog shaft 52 and the screw shaft frames 62, 63, 64, at the same time the screws 67 pick up the ensilage and drive it over into the housing 48.

Referring to Figs. 8 and 9, these are views of a modified form of boom construction adapted to fit various sizes of silos and to permit the support of the entire mechanism from three cables 40. Instead of the tubular booms 34, this preferred construction includes a plurality of channeled booms 91, which are identical in construction and three in number.

The channeled booms are attached to the housing 17 by means of metal attaching brackets 92 of substantially U-shape but having the supporting flanges 93, 94 extending diagonally upward from a yoke 95.

Yoke 95 is welded or otherwise secured to housing 17, and the flanges 93, 94 have through aper-

tures for receiving the through rivet or bolt 96 which passes through the side flanges of the U-shaped channeled booms 91.

The channeled booms 91 have their webs 97 extending vertically and their side flanges 98, 99 extending horizontally. Each boom includes a larger channel 100 and a smaller channel 101, slidably received in the larger channel.

For permitting adjustment of the length of the booms 91 the webs of the two channels 100 and 101 have a plurality of regularly spaced apertures 102 for receiving bolts by means of which they are bolted together to fit silos of different sizes.

For example, the large channel 100 may have two apertures on 6 inch centers, and the small channel 101 may have a multiplicity of such apertures on 1½ inch centers. At their outer ends the side flanges of the channels 101 are cut away, as indicated at 103, Fig. 11, leaving the web extended, as shown at 104.

The web is preferably also beveled at 105 and provided with a bore 106 for receiving a screw bolt 107 for rotatably receiving the roller 108. The roller 108 is thus pivoted on a horizontal axis for engagement with the wall of the silo as the framework moves up and down. Apertures 109 are also provided for attachment of the cables 40.

The bolts 93 for securing the booms 91 to housing 17 might permit pivotal movement, except that bracing framework is provided at 110, Fig. 9, and 111 for holding the booms rigidly in radial position.

Framework 110 may consist of three flat bars 112 twisted intermediate their ends for greater rigidity, and provided with apertures at the ends for receiving the screw bolts 113 which pass through the boom flanges and bars 112 at each corner of a triangular frame 110, tending to hold the booms rigid and readily.

In order to assure the rigidity, the second framework 111 may consist of a pair of angle iron members 114, joined together by a single bolt 115 at one of the booms and secured by being bolted at their other ends 116 to the other two booms. This provides a rigid, horizontal framework for preventing movement of the booms relative to the housing 17.

For making the booms rigid in a vertical direction, each boom is provided with a vertically extending strut 117, bolted to the boom web at 118, adjacent the housing 17. Each strut 117 is connected by means of a diagonally extending brace 119 to the boom at 120, by means of a bolt, and the strut is connected to the brace 119 at 121.

The strut 117, brace 119 and part of each boom 91 thus form a vertically rigid framework, permitting the support of the entire mechanism by means of the three cables 40, which extend upward from the ends of the booms to the pulleys 84.

Referring to Figs. 5, 6 and 7, these are views showing the gear mechanism in the gear box 49, by means of which the screw conveyors are rotated, and the driving wheel 54 is rotated at a slow speed, thus causing the screw conveyors to progress around the top of the ensilage.

This modification includes a gear housing 49a, 70 made of a plurality of pieces of sheet metal welded together to form a box. The top wall 122 of this housing supports an internal bearing supporting sleeve 123 for rotatably supporting the vertical power shaft 50.

Power shaft 50 carries a bevel gear 124 meshing with a bevel gear 125, mounted on the shaft 60 of the leading auger. Side wall 126 has a sleeve 127 welded to it for supporting the bearing for shaft 60. Shaft 60 supports a driving gear 128 which meshes with an idler 129, which in turn meshes with a spur gear 130.

Spur gear 130 meshes with the gear 131, which is carried by the trailing screw shaft 61, thereby providing for the drive of both screw shafts. Screw shaft 61 is supported in a bearing carried by sleeve 132 welded to the side wall 126. Another sleeve 133 is welded to the side wall 126 for supporting a stub shaft 134 which carries the gear 130.

Another sleeve 135 is welded to side wall 126 for supporting a bearing for a stub shaft 136 for the idler 129. The gear 130 is mounted upon a splined sleeve which also carried a pinion 137 20 driven by gear 130. Pinion 137 drives gear 138, which rotates freely upon a shaft 139 mounted in a bearing in sleeve 140.

Gear 138 is keyed by means of being mounted on a splined sleeve to a pinion 141 driven by it and meshing with a gear 142. Gear 142 rotates on shaft 134 and is keyed to a pinion 143 on the same shaft which meshes with a higher gear 144 on the driving wheel shaft 52.

Thus the driving wheel shaft 52 is driven at a reduced rate of speed while the screw shafts 60 and 61 are driven at a faster rate for chopping loose the ensilage and conveying it to the central housing 17.

The cables 40 pass over a plurality of pulleys 35 84, which are located at the ends of a tripod 85 adjacent the silo wall, and all of the cables 40, with the cable 29, are joined together and carried by one cable 86 which extends over a pulley 87 down the chute to the drum 88 of a hand operated winch 89, provided with suitable gears and a retaining dog and actuated by a crank 90.

The operation of the present silo unclader is as follows:

By means of the winch 89 and cables 86, 29 45 and 40 the mechanism may be adjusted to the proper height immediately above the ensilage, and may be permitted to feed downward if desired as the ensilage is chopped loose and conveyed to the chute 12 by the silo unloader.

More or less of the weight of the mechanism may be permitted to rest upon the ensilage by adjusting the winch 89, and this also adjusts the rate of feed.

The motor 44 is controlled by a switch adjacent the bottom of the chute, and when the motor is driven it drives the shaft 45 and screw 28, which lifts the ensilage from the housing 48 and deposits it upon the conveyor 19.

Conveyor 19 is driven through suitable gearing from the same motor and its belt carries the ensilage radially from the screw 28 to the chute 12.

The same motor through suitable gears drives the screw shafts 60, 61, and screws 67 and 68 which chop the ensilage loose, tending to elevate it between the screws and to cause it to progress radially inward into the housing 48.

As the ensilage is lifted from beneath the screws 67, 68, and conveyed to the housing 48, the frame members 62, 63, 64 for screws 67, 68 are caused to rotate by the fact that the same motor drives the tubular shaft 52, and dog wheel 54, which rotates housing 48, and causes the screws to progress around the surface of the ensilage in the silo. This constantly assures the

location of the screws over new ensilage at the same level, which is picked up and delivered to the housing 48 by the screws.

The drive to the shaft 52 and screw shafts 60, 61 is through the ring V-pulleys 73 which rotate on the main housing 17 and permit shaft 79 to remain in the same vertical position, while shaft 50 revolves about the housing 17 with the housing 48, gear box 49 and the screws 67, 68.

It will thus be observed that we have invented a new mechanical drive for silo unloaders, and a completely mechanical mechanism for conveying ensilage which is broken loose from the mass and conveyed to the chute without utilizing any blowers, which we have found to be undependable for this purpose.

The ensilage varies according to its weight and frozen condition, but no matter what its condition is, it will be broken up and conveyed by the present mechanical arrangements.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States, is:

1. In a silo unloader of the type having a central housing, an upward conveyor in said housing, a radial conveyor for carrying ensilage from said upward conveyor to a silage chute at the edge of the silo, and conveyor means for conveying ensilage from the free surface of the ensilage to said upward conveyor at the bottom of said central housing, the improvement which comprises an electric motor mounted upon the upper end of said housing, and having a vertical motor shaft, bearings carried by said housing and located in alignment with each other on an axis parallel to said motor shaft, a second shaft in said bearings, driving connections between said shafts, a lower housing rotatably mounted on said central housing, a rotatable drive boom extending radially from said lower housing, and having a drive wheel resting on the ensilage, a pair of adjacent, oppositely rotating screw conveyors carried by said lower housing and housed on their outer sides by lateral frame members, said screw conveyors engaging the ensilage at their lower edges, and operative mechanical driving connections between said second shaft and said rotatable drive boom and said screw conveyors to cause said drive wheel to rotate said lower housing and to cause said screw conveyors to rotate and to sweep over the surface of the ensilage beneath them, and to convey ensilage to said central housing.

2. In a silo unloader of the type having a central housing, an upward conveyor in said housing, a radial conveyor for carrying ensilage from said upward conveyor to a silage chute at the edge of the silo, and conveyor means for conveying ensilage from the free surface of the ensilage to said upward conveyor at the bottom of said central housing, the improvement which comprises an electric motor mounted upon the upper end of said housing, and having a vertical motor shaft, bearings carried by said housing and located in alignment with each other on an axis parallel to said motor shaft, a second shaft in said bearings, driving connections between said shafts, a lower housing rotatably mounted on said

central housing, a rotatable drive boom extending radially from said lower housing, and having a drive wheel resting on the ensilage, a pair of adjacent, oppositely rotating screw conveyors carried by said lower housing and housed on their outer sides by lateral frame members, said screw conveyors engaging the ensilage at their lower edges, and operative mechanical driving connections between said second shaft and said rotatable drive boom and said screw conveyors to cause said drive wheel to rotate said lower housing and to cause said screw conveyors to rotate and to sweep over the surface of the ensilage beneath them, and to convey ensilage to said central housing, said screw conveyors each having a shaft and a pair of sections of screw flange of different pitch, the outermost section of each screw flange having a multiplicity of turns of less pitch closer together, to work the ensilage loose more thoroughly at the outer part of the silo.

3. In a silo unloader of the type having a central housing, an upward conveyor in said housing, a radial conveyor for carrying ensilage from said upward conveyor to a silage chute at the edge of the silo, and conveyor means for conveying ensilage from the free surface of the ensilage to said upward conveyor at the bottom of said central housing, the improvement which comprises an electric motor mounted upon the upper end of said housing, and having a vertical motor shaft, bearings carried by said housing and located in alignment with each other on an axis parallel to said motor shaft, a second shaft in said bearings, driving connections between said shafts, a lower housing rotatably mounted on said central housing, a rotatable drive boom extending radially from said lower housing, and having a drive wheel resting on the ensilage, a pair of adjacent, oppositely rotating screw conveyors carried by said lower housing and housed on their outer sides by lateral frame members, said screw conveyors engaging the ensilage at their lower edges, and operative mechanical driving connections between said second shaft and said rotatable drive boom and said screw conveyors to cause said drive wheel to rotate said lower housing and to cause said screw conveyors to rotate and to sweep over the surface of the ensilage beneath them, and to convey ensilage to said central housing, said screw conveyors each having a shaft and a pair of sections of screw flange of different pitch, the outermost section of each screw flange having a multiplicity of turns of less pitch closer together, to work the ensilage loose more thoroughly at the outer part of the silo, and the screw flanges being provided with a multiplicity of knives projecting outwardly to cut frozen ensilage loose from the mass of ensilage in the silo.

4. In a silo unloader of the type having a central housing, an upward conveyor in said housing, a radial conveyor for carrying ensilage from said upward conveyor to a silage chute at the edge of the silo, and conveyor means for conveying ensilage from the free surface of the ensilage to said upward conveyor at the bottom of said central housing, the improvement which comprises an electric motor mounted upon the upper end of said housing, and having a vertical motor shaft, bearings carried by said housing and located in alignment with each other on an axis parallel to said motor shaft, a second shaft in said bearings, driving connections between said shafts, a lower housing rotatably mounted on

said central housing, a rotatable drive boom extending radially from said lower housing, and having a drive wheel resting on the ensilage, a pair of adjacent, oppositely rotating screw conveyors carried by said lower housing and housed on their outer sides by lateral frame members, said screw conveyors carried by said lower housing and housed on their outer sides by lateral frame members, said screw conveyors engaging the ensilage at their lower edges, and operative mechanical driving connections between said second shaft and said rotatable drive boom and said screw conveyors to cause said drive wheel to rotate said lower housing and to cause said screw conveyors to rotate and to sweep over the surface of the ensilage beneath them, and to convey ensilage to said central housing, said driving connections 15 including a pair of connected ring driving mem-

bers rotatably mounted on said lower housing, one of said ring driving members being driven from said second shaft, a reduction gear driving said rotatable boom at a suitable wheel speed, and driving said screw conveyors at a faster speed, and having a vertical shaft driving the said reduction gears from the other ring member.
